BEVERAGE COOLER

Thomas J. Fegley, Jenkintown, Pa., assignor to
North Bro's Mfg Co., Philadelphia, Pa., a
corporation of Pennsylvania

Application June 23, 1933. Serial No. 677,312

7 Claims. (Cl. 62—34)

An object of this invention is to provide novel and efficient means for the rapid cooling of bottled beverages, and to this general end, the invention contemplates the provision for conjoint 5 operation of a receptacle for the said bottles and an ice crusher, with means for detachably mounting the crusher on the receptacle in position to discharge the crushed ice into the interior of the latter.

10 Another object of the invention is to provide a cooling device of the stated character which shall also constitute means for readily transporting the bottled beverage and for maintaining it over a considerable period of time in a desirably 15 cool condition.

Still another object of the invention is to provide a cooler of the stated character which shall be adapted for the rapid and efficient cooling of both relatively small and large numbers of bottles of beverage as the requirements may demand.

In the attached drawings:

Figure 1 is a view in perspective of the receptacle and crusher assembly;

Fig. 2 is a view in perspective of the receptacle 25 with the crusher removed and with the top plate in position;

Fig. 3 is a fragmentary sectional view showing a detail of the receptacle and crusher assembly, and

30 Fig. 4 is a view in perspective of the lower end of the crusher-supporting stem.

With reference to the drawings, a preferred embodiment of my invention comprises a receptacle 1 having in the interior thereof partitions 35 2, 3 and 4 which extend radially from a central member 5 and which with said central member define within the interior of the receptacle three separate compartments numbered, respectively, 6, 7 and 8. Each of these compartments in the 40 present instance is adapted to receive two bottles of standard size, and as shown in Fig. 2 are of such depth that only the tops of the bottles project above the upper edges of the compartments. The central member 5 has in its upper 45 surface a socket 9, and at the upper end of the socket three radial recesses 10, 11 and 12, the socket 9 being in the present instance of cylindrical form and adapted for reception of the lower end of a stem 13 which at its upper transversely 50 extending end carries an ice crusher 14. This crusher, which may be of a variety of different forms but which preferably is formed in accordance with the principles disclosed in the copending application of myself and George O. Leopold, filed

when the stem 13 is inserted in the socket 9, as illustrated in Fig. 1, to occupy a position above the receptacle, wherein the crushed ice discharged from the crusher may enter the interior of the receptacle. In order to securely hold the crusher during the crushing operation in positions over the individual compartments 6, 7 and 8, I provide the stem 13, as shown in Figs. 3 and 4, with a radially projecting lug 15 which, when the stem is inserted in the socket 9, enters one or other of the radial recesses 10, 11 and 12. The lug 15 projects from the stem in alignment with the crusher 14, while the recesses 10, 11 and 12 are in line individually with the centers of the compartments 6, 7 and 8, so that when the lug 15 occupies any 70 one of the recesses the crusher 14 is held in a position substantially over the center of the compartment toward which the particular recess extends. By slightly elevating the stem 13 in the socket, the crusher may be turned to positions overlying 75 the other compartments, in which positions it is held by engagement of the lug 15 in the associated recess.

Secured to the central member 5 of the receptacle 1 is a handle 16 so formed as to offer no 80 interference to insertion of the stem 13 of the crusher in the socket 9. I also preferably provide a cover member 17, see Fig. 2, which member is provided with a series of openings 18 through which the upper ends of bottles positioned in the various compartments may project, as shown in broken lines. This cover plate rests upon an internal shoulder 19 of the receptacle 1 and is provided at the center with a suitably formed opening 20 for passage of the handle 16. 90 The cover preferably has at one or both sides handles 21 facilitating removal. Following the introduction of the crushed ice into those of the compartments 6, 7 and 8 of the receptacle which contain bottles and subsequent removal of the 95 crusher from the receptacle, the lid 17 may be applied as shown in Fig. 2. In this condition, the receptacle affords a ready means for conveying the bottles to a remote point for consumption of the beverage, which will be kept 100 cool for a considerable length of time by the ice within the compartments.

The device affords a simple and effective means for the rapid cooling of beverages in bottles. The construction is such that the ice is kept in 105 intimate contact with the outer surfaces of the bottles, and by making the compartments 6, 7 and 8 of such size that there is little clearance between the walls thereof and the contained bottles, the cooling may be accomplished rapid- 110

ly with only a relatively small quantity of ice. Where it is desired to maintain the cooling action over a longer period of time, the compartments may be made larger relative to the size 5 of the bottles so that originally larger quantities of ice may be introduced.

While the invention is described primarily as a means for cooling bottled beverages, it will be understood that the device in principle may 10 equally well be employed to cool beverages or other liquids in containers other than bottles. It will be apparent also that there may be considerable modification in the form of the device as herein described and illustrated without 15 departure from the invention.

I claim:

1. In a cooler for bottled beverages, the combination with a receptacle for said bottles, of an ice crusher, and means for detachably mounting 20 the crusher on the receptacle in position to discharge crushed ice into the interior of the latter.

2. In a cooler for bottled beverages, the combination with a receptacle having a plurality of compartments for said bottles, of an ice crusher, and means for mounting the crusher on the receptacle in position to discharge crushed ice into the interior of the latter, said mounting permitting 25 adjustment of the crusher to positions overlying the individual compartments.

3. In a cooler for bottle beverages, the combination with a receptacle comprising a plurality of compartments for reception of the said bottles, of an ice crusher, means for mounting the crusher 30 on the receptacle for adjustment to positions overlying the individual compartments, and means for anchoring the crusher in the respective adjusted positions.

4. In a cooler for bottled beverages, the combination with a receptacle for said bottles having a socket, of an ice crusher having a portion adapted to enter said socket to thereby support the crusher on the receptacle in position to discharge crushed ice into the interior of the latter. 80

5. In a cooler for bottled beverages, the combination with a receptacle for said bottles, of an ice crusher, and means for detachably mounting the crusher on the receptacle in an elevated 85 position whereby crushed ice may pass from said crusher into the interior of the receptacle by gravity.

6. In a cooler for bottled beverages, the combination with a receptacle for said bottles, of an ice crusher mounted on said receptacle in an elevated position permitting passage of crushed ice from the crusher to the interior of the receptacle by gravity. 90

7. In a cooler for bottled beverages, the combination with a receptacle, and partitioning means dividing the interior of the receptacle into a plurality of compartments, said partitioning means having in the top thereof a socket and said socket having radial slots projecting transversely from the upper end thereof toward the said compartments of the receptacle, of an ice crusher having a member adapted to fit said socket to support the crusher in an elevated position, and a projection on said member adapted when the latter is inserted in the socket to enter said slots individually to thereby locate and retain the crusher releasably in adjusted positions respectively overlying the compartments. 105
